UNITED STATES PATENT OFFICE

2,456,339

PUMP CONSTRUCTION

Darwin B. Stricklin, Milwaukee, Wis.

Application June 25, 1946, Serial No. 679,158

1 Claim. (Cl. 103—41)

1

This invention relates to improvements in liquid pumps, having for an object to provide a durable and constructionally simple, though highly efficient, pump especially advantageous for use in pumping various liquids, as for example, oils and similar matters, to hydraulic motors, hydraulic rams and various other hydraulically operated apparatuses and devices for their operation.

It is also an object of the invention to provide a pump of the indicated character, which is of compact and small size and is capable of quantity production at a minimum of cost.

Moreover, the invention aims to provide a liquid pump whose body or casing is of one-piece construction and has bores or other openings formed therein in a highly novel and advantageous manner and relationship, adapted to function as plunger and valve receiving chambers or cylinders and as fluid conducting ingress and egress ways.

In the present time production of liquid pumps of the types herein concerned, it is a recognized and well-established fact that piston or plunger cylinders, valve cylinders, and other and necessary parts of a pump casing, are required to be honed or lapped to very close tolerances. In pump constructions wherein this type of precision work must be done, considerable and costly labor is entailed in the accurate and efficient attainment and/or holding of such tolerances, especially, where "blind" or non-through bores or openings in pump casings are encountered, with the result that production costs—both of labor and piece loss—are materially increased.

By means of my invention, and particularly, the novel formation and arrangement of bores in the pump casing, the above stated difficulties are eliminated, specifically, due to the reduction to minimum of "blind" or non-through bores. In consequence, in producing said pumps, an overall efficiency is attained with a minimum of labor, material and time outlay.

The foregoing, as well as other objects, advantages and meritorious teachings of my invention, will be in part obvious and in part pointed out in the following detailed disclosure thereof, when taken in conjunction with the accompanying drawings, it being understood that the form of the invention presented herein is precise and what is now considered to be the best mode of embodying its principles, but that modifications and changes may be made in specific embodiments without departing from its essential features.

In the drawings:

Figure 1 is a top plan view of my improved pump, showing it installed.

Figure 2 is a vertical longitudinal section through a liquid tank or reservoir which receives and supports my improved pump therein, the latter being shown in side elevation.

2

Figure 3 is a detail in transverse section taken on the line 3—3 of Figure 2, looking in the direction in which the arrows point.

Figure 4 is a vertical longitudinal section through the improved pump and the liquid tank receiving and supporting it therein.

Figure 5 is a vertical transverse section taken on the line 5—5 of Figure 2, looking in the direction in which the arrows point, and

Figure 6 is a fragmentary detail in vertical transverse section, taken on the line 6—6 of Figure 2, looking in the direction in which the arrows point.

Referring in detail to the accompanying drawings, I have therein shown my pump operatively associated with a liquid supply tank or reservoir T, whose normally upper end is partially closed by a plate P engaged over its marginal portions. Fluid or liquid-tight connection is effected between the engaged portions of the tank and the plate by the interpositioning of a suitable packing p and then passing screws s through adjacent portions of said plate into threaded engagement with the appropriate aligned pockets or openings in the tank sides. Note that the plate P has a medially located rectangularly shaped opening o formed in the same, the purpose of which will be presently apparent.

The improved pump comprises a cast or otherwise formed generally rectangular body block 1, of metal or other suitable material, having a laterally extending flange 2 integral with and arranged entirely about its normally upper end, and an internally threaded nipple extension 3 on the lower enlarged rounded end 4 of one of its sides. A portion of one side of the body is dished, as at 5, to facilitate its engagement into the rectangular opening o in the plate P, whereby the same will be dependably supported from said plate in the manner shown in Figures 2, 4 and 5 of the drawings.

To firmly or solidly support the body 1 in depending relationship from the plate P and to effect fluidtightness between the pump body 45 flange 2 and adjacent portions of the plate P, a packing, gasket or other suitable device g is interposed between adjacent and relatively overlapped parts of the flange and the plate (see Figure 4). Thereupon, bolts, screws or other connecting devices b are engaged through appropriate portions of the flange 2 with corresponding portions of the plate P, to the required extent.

The body 1 is formed with vertical and relatively parallel bores 6, 7 and 8. The bores 6 and 55 8 extend entirely through the body, opening onto the upper and lower sides of the same, while the bore 7 opens onto the upper side of said body and its lower end terminates therewithin in communication with a reduced vertically aligned way or 60 duct 7' opening onto a horizontally and some-

what enlarged way 9 in the body, hereinafter more fully described, as is well shown in Figure 4 of the drawings.

Counter-bores 6' and 8' are made in the upper end portions of the bores 6 and 8, respectively, and communicate with downwardly directed drain holes 10 and 11 discharging outwardly of the body 1 beneath the flange 2, thus providing for trapping of amounts of by-passed pumped liquid in such counter-bores and its return, by drainage, through said holes to the liquid tank or reservoir T. In this manner, a material manufacturing economy is effected, due to the elimination of the need or use of packings and packing nuts at the upper ends of said bores 6 or 8.

The horizontal way 9, above referred to, is preferably circular in cross section. It opens onto the nipple extension 3, intersects and communicates with the lower end of the bore 6 intermediate thereof, and extends inwardly of the body 1 to a point below the bore 7 and communicates with the lower end of the reduced duct 12'. The inner end of said way is in spaced relation to the bore 8.

To effect liquid return to the supply tank T from the bore 7, a horizontal duct or way 12 is formed in the body 1. The inner end thereof opens into a lower portion of said bore and its outer end, onto one side of the body, while an intermediate portion intersects and communicates with the adjacent and intermediate portion of the bore 8 (see Figure 4).

As shown in Figures 4 and 5 of the accompanying drawings, the lower end of the bore 6, i. e., that portion through the enlarged end 4, has a greater diameter than the body of said bore and is, preferably, formed with an internal annular shoulder. A suction actuatable and spring returned stem valve seating and retaining member 13, of generally circular shape, is positioned adjacent the described open enlarged end 4 of the body 1. The normally inner side of the same is annularly shouldered, as at 14, and so sized as to be snugly engaged and received in and by the aforesaid internal annular shouldered portion of the open enlarged end 4. Fluid-tight connection between the member 13 and the adjacent portion of the lower side of the enlarged end 4 of the body 1, is effected by arranging suitable packing 15 between adjacent portions thereof, thereupon passing connecting screws 16 through appropriately arranged and formed openings in the member 13 into screw threaded engagement with adjacent portions of the body 1.

The member 13 is formed or otherwise provided with a chambered valve seat 17 and has ingress ways or ducts 18 formed therein communicating with said chamber and opening outwardly of the member. A valve 19 is engaged on the chambered valve seat 17 and has its stem 19' slidably received through an adjacent sleeved portion of the member 13. An expandable coiled spring 20, having one end engaged with an adjacent portion of the member 13, and its opposite end about and with an appropriate portion of the outer end of the valve stem 19', as at 21, serves to normally retain the suction actuated stem valve in seated engagement with the member 13.

The outer end of the horizontal way 9 is closed by a screw-threaded plug 22 turned into engagement with the internally threaded nipple extension 3. Thus, access may be had to the former, as and when required.

Slidably received within the bore 6 is a cylindrically shaped pump plunger 23 carrying suit-

able packing 24 on its lower end; its upper end being formed, as at 25, for pivotal connection with the free end of an eccentric operated pitman 26, the eccentric 27 of which is connected to a suitable motor or other power supply means, not shown.

The upper end of the bore 7 has one part of a coupling or union 28 engaged therein (see Figure 4), while a discharge conduit 29, or like means, is connected to its opposite end and thus, provides for the conduction of pump fluid from the bore 7 to its point of ultimate use.

Seated in the lower and remaining end of the bore 7, normally closing the duct 7', is a spherical valve 30, whose disposition or arrangement is such that it will control communication between the way 9, the duct 7, and the horizontal duct 12. Said spherical valve 30 is normally retained in its seated or closed position through the medium of an expandable coiled spring 31 arranged in and longitudinally of the bore 7, one end of which bears on a suitable fitting 32 engaging the valve 30, while its opposite end has fixed bearing with the adjacent inner end portion of the coupling 28. At this point, it is to be understood that the tension of the expandable coiled spring 7 is such that when oil or other liquid is pumped through the duct 7', the pressure imparted thereto will be entirely sufficient to unseat the spherical valve 30; hence, permitting its outflowing from the bore 7 through the discharge conduit 29 or, if desired, through the horizontal duct 12 for bypassing back into the supply tank T.

In order that by-passing of oil or liquid from the bore 7 through the horizontal duct 12 into the supply tank T may be electively controlled, a cylindrical valve 33 is slidably received in the bore 8. The upper or outer end of said valve is formed or otherwise prepared, as indicated at 34, to permit the connection of suitable operating mechanism 34' thereto for imparting sliding movement to the same. Thus, with inward positioning of the cylindrical valve 33, it will be seen that the lower portion thereof will be engaged across or over the intermediate portion of the horizontal duct 12, and in consequence, flow of oil or liquid from the bore 7 through said duct into the tank T, will be prevented. However, should the cylindrical valve 33 be moved upwardly in its bore 8 to a point above or beyond the horizontal duct 12, passage of oil or liquid will be then permitted through the latter from the bore 7 and by-passed into the supply tank T. By the same token, the rate of by-passing or flow of oil or liquid through said horizontal duct 12 from the bore 7 into the supply tank T, may be effectually modulated by appropriately varying the positioning of the lower end portion of the valve 33 with relation to the horizontal duct 12, thereby increasing or diminishing the size of the orifice or way.

To install or attach my improved pump to a tank such as herein indicated by the reference letter T, the body 1 of the pump is endwise inserted through the opening in the plate P. To effect such insertion, the body 1 is arranged in an oblique or canted position with relation to the opening in said plate P and is then moved, endwise, downwardly through the opening therein. As it is moved downwardly into the tank T, the dished portion 5 on one side of the body permits it to be moved to a position at substantially right angles to the plate P, allowing the flange 2 to flushly engage with or contact the packing or gasket 9. Thereupon, the connecting devices 5

are engaged and the pump 6 secured in an immovable relation to the tank T and its plate P. Connections are effected between the pump plunger 23 and its eccentric driving means and the cylindrical valve 33 and its operating means 34'. Fluid is supplied to the proper level in the tank T.

Upon reciprocation of the pump plunger 23, and particularly, during the upstroke thereof, oil or other liquid will be drawn from the supply tank T through the ingress ducts 18 of the valve seating and retaining member 13 into the chambered valve seat 17. With upward or unseating movement of the spring retained stem valve 19, under urge of suction applied thereto from the plunger 23, said liquid will be drawn by the valve and upwardly into the pump cylinder or bore 6. Upon downward stroke of the pump plunger 23, and assuming that the cylinder valve 33 has been moved to its closed position, as shown in Figure 4 of the drawings, the liquid will be forced downwardly from the bore 6 through the horizontal way 9, thence upwardly through the duct 7' by the pressure unseated spring retained spherical valve 30 into the bore 7 from whence it will discharge from the bore via the discharge conduit or connection 29 to its point of usage.

Should it be desired to by-pass the liquid from the discharge conduit 29, the cylinder valve 33 slidably operating in the bore 8, is moved to uncover or partially uncover, or open, the horizontal by-passing duct 12. With the cylinder valve 33 thus adjusted or positioned, liquid discharged under pressure from the way 9 by means of the pump plunger 23, will move upwardly through the reduced duct 7', unseating the spring retained spherical valve 30, whereupon it will flow through the horizontal by-passing duct 12 back into the tank T. As heretofore explained, the rate of discharge or by-passing of liquid from the bore 7 into the tank T may be regulated to the desired nicety or degree by adequate vertical adjustment of the cylindrical valve 33 with relation to said by-passing duct 12.

Such liquid as may by-pass the plunger 23 and/or the cylindrical valve 33 and reach the upper portion of their respective bores 6 and 8, will be trapped in the counter-bores 6' and 8', from which it will drain through their respective openings 10 and 11 back into the tank T.

Inspection, repair or removal of parts of my improved pump may be readily effected. Such inspection, repair or replacement may be effected (1) by removing the valve seating and retaining member 13 from the lower end of the pump body 1; (2) by removing the screw closure plug 22 from the nipple extension 3 of the body 1, thus revealing the interior of the passage way 9; (3) "pulling" the pump plunger 23 and/or the cylindrical valve 33 from their respective bores 6 and 8, or (4), in the case of the active parts housed in the bore 7, by removing the coupling 28, thus giving access to the same and said parts.

As hereinbefore set forth, a pump constructed in accordance with the teachings of my invention is capable of mass production at a minimum of cost and with a maximum of manufacturing economies, particularly, because of the manner or method of forming the bores 6, 7 and 8 in the pump body block 1. Precision work necessary to be done in connection with the bores 6, 7 and 8 can be effected with but a minimum of labor and time expenditure, and proper tolerances can be attained and held. Moreover, the number of

boring operations necessary for the forming of the bores 6, 7 and 8, the ways 9 and 12, and the duct 7', whereby to effect the hereinbefore described intercommunication or interrelationing therebetween, is maintained at strictly minimum, plus avoiding the necessity of making "blind" or non-through bores or holes in the pump body block 1.

It will be readily understood by skilled artisans that my improved pump is capable of many usages; also, that the size of such pump and/or its assembly or any one or more of the parts thereof, may be increased or decreased, such as conditions or preference may dictate.

I claim:

15. A body block for pumps, consisting of a single piece of material, a flange integral with the upper side of the block extending horizontally and outwardly therefrom entirely thereabout and having its under surface flat throughout the entire area thereof, said body having a plurality of spaced and parallel vertically disposed straight bores therein opening onto its upper side inwardly of said flange, certain of said bores terminating in the block in spaced relation to its lower side, and 20 the remaining bore extending entirely through the block and opening onto its lower side, a portion of said block intermediately of its upper and lower sides having a straight horizontal bore therein opening onto one vertical side thereof and its inner end terminated within the block, said horizontal bore communicating with the lower ends of said certain bores, means normally closing the outer end of said straight horizontal bore, an intermediate and lower side portion of the horizontal bore opening onto said lower side of the body, another portion of the body having a second straight horizontal bore therein communicating with one of said certain bores and said remaining bore intermediately of the opposite 25 ends of the latter bore and opening onto the opposite vertical side of the block, the upper ends of all said bores being enlarged adjacent and at their respective points of opening onto the upper side of the block, and said block having downwardly directed drain openings in portions of the same communicating with the enlarged upper ends of said certain and remaining bores and opening onto said vertical sides of the block below the under side of said flange, a reciprocal 30 plunger received in one of said certain bores and extending from its upper end, check valve means in the other of said certain bores adjacent its point of communication with the first mentioned horizontal bore, and a cylindrical valve reciprocally received in said remaining bore engageable over and across said second horizontal bore at its points of communication with said remaining bore.

DARWIN B. STRICKLIN.
